UNITED STATES PATENT OFFICE

ARTHUR THOMAS, OF THORNTON HEATH, ENGLAND, ASSIGNOR TO THE ACCOUNTING & TABULATING CORPORATION OF GT. BRITAIN, LIMITED, OF LONDON, ENGLAND

PUNCHING MACHINE

Application filed December 21, 1927, Serial No. 241,718, and in Great Britain February 4, 1927.

This invention relates to duplicating or transfer punching machines, used for duplicating master records such as the perforated cards used in statistical, calculating and like machines.

A main object of the present invention is to increase the working speed of such machines.

With such an object:—

10 The invention consists in the combination of elements hereinafter described and particularly pointed out in the claims.

The invention will now be described with reference to the accompanying drawings, in 15 which:—

Figure 1 is a general arrangement of a punching machine for cards;

Figure 2 is an enlarged view of the sensing unit, and

20 Figure 3 is a detail.

In carrying the invention into effect according to the form illustrated as used for duplicating or transferring the data from master statistical record cards having perforations therein to other blank cards or reproductions, two hoppers, A, B, are provided, one above the other, the upper, A, for the master cards and the lower, B, for the blank cards which are to be punched 25 in exact accordance with the master cards.

The two hoppers are provided with picker knives C, D, and throat knives, E, F, as well as the feed rolls, G, H, situated just outside the throat knives to feed the cards from 35 their respective hoppers between the perforated plates, I, J, of the two pin-boxes which are arranged vertically and co-axially above one another.

The punching- and sensing-pin boxes are 40 reciprocated vertically by means of a connecting rod, M, and link, N, driven from a suitable shaft by means of an eccentric, O. The sensing-pin box is moved the whole travel of the eccentric but the lower or punching- 45 pin box is only moved a proportion of the stroke by means of links, P, Q, pivoted at one end to the connecting rod and at the other end to links, R, S, secured to the frame of the machine to form a kind of toggle joint. The mid points of these links, P, Q,

are connected to the punching-pin box. Thus, the ratio of the strokes is approximately two to one.

The sensing-pin box is provided with a card stop, T, to keep the master record in 55 the correct position for sensing and with delivery rolls, U, which feed the records into the bin, V. The punching-pin box is likewise provided with a card stop, W, and feed rolls, X, for delivering the reproductions 60 into a bin, Y.

The sensing device comprises a number of sensing pins, 1, arranged in rows corresponding to the possible total number of holes in a record card. These pins have 65 heads, 2, which rest upon a horizontal supporting plate, 3, fixed to the pin-box and enter the top perforated plate, I. Above these sensing pins, 1, are a corresponding number of set bars, 4, which rest upon the 70 heads, 2, of the pins and are suitably guided in perforated plates, 5 and 6, mounted on the pin-box. Above the set bars are a corresponding number of presser pins, 7, which are guided in plates, 8 and 9, and are pressed 75 down on the set bars, 4, by means of helical springs, 10, which are situated between collars, 11, on the presser pins and the plate, 9, mounted upon the top of the pin-box in which the presser pins are guided. Each 80 sensing pin, 1, is co-axial with its respective set bar, 4, and presser pin, 7.

Each set bar, 4, is of a particular formation as shown in Figure 3, having on one side a projection, 13, the top, 14, of which is 85 horizontal, the side, 15, vertical and the bottom, 16, sloping downwards at an angle of about 45° to join the bar. The other side of each set bar, 4, has a recess, 17, the top, 18, of which is horizontal, the side, 19, 90 vertical and the bottom, 20, sloping downwards at the same angle as the bottom, 16, on the opposite side, the two sloping portions, 16 and 20, being situated substantially on a level.

Each row of pins is provided with a locking bar, 22, which is formed by a vertical plate having a number of small horizontal projections, 23, on its lower edge one for each set bar, which projections co-act with 95

the slanting portions of the set bars. Each projection has the top and bottom horizontal, and one side vertical, while the other side slopes and engages the portion, 16, on the set bar, 4. These locking bars, 22, are pressed by means of springs, 24, so that they always tend to move away from the projections upon the set bars. The locking bars are carried by the frame of the pin-box and are reciprocated up and down therewith.

The sloping part of the recesses of the set bars is so arranged that when the pin-box descends and the two sensing pins which do not enter perforations rest upon the card, the continued descent of the pin-box brings the projections, 23, on the locking bars in contact with the sloping portions, 20, and moves the locking bars to the right in Figure 2, so that the projections, 23, slide over the tops of the projections, 13, on the set bars which have entered perforations. Further descent of the pin-box will press the set bars upon the heads, 2, of the sensing pins, 1, through direct contact of the projections, 23, on the locking bars, 22, with the projections, 13, on the set bars.

In the bottom perforated plate, I, on which the master record rests are situated a number of intermediate pins, 26, the lower ends of which are reduced in diameter and rest upon the heads, 27, of punches, 28, situated in the punching-pin box, the heads of the punches resting upon a horizontal plate, 29, attached to the pin-box and forming a guide, suitable guides, 30 and 31, also being provided for the intermediate pins. The bottom ends of the punches, 28, are located in the top perforated plate, J, between which and the bottom perforated plate, J, the blank cards to be punched are placed.

Each locking bar, 22, is provided with a locking latch or pawl, 33, pivoted on a rod, 34, secured to the frame of the pin-box. When a pawl, 33, is placed in the portion shown by dotted lines it enables any sensing pins to be cut out from functioning as for instance the seven pins shown on the right of Figure 2. It also enables any number of pins to be used for punching holes at every stroke of the machine as for instance the five sensing pins shown on the left of Figure 2. Any combinations of these two functions may also be obtained.

In operation the cards are fed between the perforated plates, I and J, and the upper and lower pin-boxes while the rotation of the eccentric slowly brings the two pin-boxes down to their lowermost position. As all the potential rows of perforations are sensed the sensing pins, 1, pass through the holes in the card and the further descent of the pin-box moves the locking bars, 22, so as to lock these pins in their downward position by means of the sensing pins which have not entered perforations in the card, as ex-

plained above. Continued downward movement of the two pin-boxes brings the sensing pins which have entered perforations in direct contact with intermediate pins and presses them upon the heads of the punches which are thus thrust through the cards and perforate them in the desired position.

Upward movement of the pin-boxes restores the punches to their normal position and raises the intermediate pins and sensing pins as well as the set bars, until in the final position the locking bars are restored by the springs, 24, to their normal position, unlocking the sensing pins which passed through the perforations by means of the projections on the locking bars sliding back into the recesses, 17, on the set bars. Just before the pin-boxes have attained their highest position the cards are ejected by means of rolls and are fed into hoppers, 85 V and Y.

It will thus be seen that a duplicate of the master card is produced at one single operation and that the sensing pins themselves act to operate the punches directly.

If desired the pin-boxes may be arranged horizontally or in any other position as long as the movable pins, punches, and the like are co-axial.

In the example described only one reproduction of each master record is produced but any number of reproductions can be made by having one or more master records and continually feeding them in to the sensing device.

It is to be understood that the invention is equally applicable to producing Jacquard loom cards, rolls for piano players or the like having perforations.

Having now described my invention what I claim as new and desire to secure by Letters Patent is:—

1. A punching machine for duplicating a perforated card of the kind indicated, comprising in combination a pattern card; a series of sensing pins aligned with perforation positions on said card, a series of punching pins adjacent a card to be punched and aligned with said sensing pins; means for carrying said sensing pins; means for moving said carrying means in relation to said pattern so that certain of said sensing pins pass through said card when corresponding perforations are present and certain other of said sensing pins are held by said card when no corresponding perforations are present; means for locking said pins that have passed through said perforations, said locking means including said certain sensing pins held by said card, continued movement of said carrying means due to said moving means causing said locked pins to operate corresponding pins of said aligned series of punching pins.

2. A punching machine for duplicating

a perforated card of the kind indicated, comprising in combination a pattern card; a series of sensing pins aligned with perforation positions in said card; means for carrying said sensing pins; a series of 5 punching pins aligned with said sensing pins and disposed adjacent a card to be punched; means for carrying said punching pins; and means for moving said sensing- 10 pin carrying means and said punching-pin carrying means differentially as regards travel in relation to said cards.

3. A punching machine as claimed in claim 2, in which said moving means includes a driving rod operatively connected to said sensing-pin carrying means and a toggle-like device operatively connected between said driving rod and said punching- 15 pin carrying means.

20 4. A punching machine for duplicating a perforated card of the kind indicated, comprising in combination a pattern card; a series of sensing pins aligned with perforation positions in said card; means for carrying said sensing pins; a series of punching pins in alignment with said sensing pins; means for carrying said punching pins; means for placing sensing pins selected by 25 perforations in said card into operative relation with corresponding punching pins; and common means for reciprocating said sensing-pin and said punching-pin carrying means alternately to move certain of said punching pins to effect a punching operation 30 and withdraw the punching pins engaged in said punching operation.

5. A punching machine for duplicating a perforated card of the kind indicated, comprising in combination, a pattern card; 40 means for supporting the card to be duplicated; means aligned therewith for supporting a card to be perforated; sensing pins and means for carrying them, said sensing pins being yieldably mounted in said carrying means; punching pins aligned with said sensing pins; and automatic means acting by a continuous movement in one direction to sense the perforations in said card to be duplicated, to lock those selected sensing 45 pins that have passed through perforations to said carrying means and to bring said selected sensing pins into operative relation with corresponding punching pins to actuate the latter.

55 6. A punching machine for duplicating a perforated card of the kind indicated, comprising in combination a series of sensing pins and a co-operative series of aligned punching pins respectively disposed adjacent a pattern card and a card to be perforated; and means for moving said sensing and punching pins in the same direction to perform their sensing and punching functions, certain of said sensing pins as determined by the perforations in said pattern 60

card selecting the punching pins that perform the punching operations.

7. A punching machine for duplicating a perforated card of the kind indicated comprising in combination a series of sensing pins and a co-operative series of aligned 70 punching pins respectively disposed adjacent a pattern card and a card to be perforated; stationary means for supporting said pattern card and said card to be perforated and means for moving said sensing and punching pins in the same direction to perform their sensing and punching functions, certain of said sensing pins as determined by the perforations in said pattern 75 card selecting the punching pins that perform the punching operations.

In testimony whereof I have signed my name to this specification.
